UNITED STATES PATENT OFFICE

HUBERT A. MYERS, OF TOLEDO, OHIO, ASSIGNOR TO THE MYERS REGULATOR COMPANY, OF TOLEDO, OHIO, A CORPORATION OF OHIO

WINDOW REGULATOR

Application filed May 3, 1926. Serial No. 106,220.

My invention has for its object to provide a window regulator having operating gear and a mounting plate therefor that are so constructed and arranged that relative displacement of the gear and the consequent stripping of the gear by the severest strains that the window regulator could possibly be subjected to in its use, is prevented. The invention is particularly applicable to the 10 pinion and sector type wherein an arm secured to the sector engages the lower edge of the window at the outer end of the arm and which is thus subjected to a severe, more or less, twisting strain upon movement of the 15 window particularly if the window sticks or is engaged in its guiding channels.

The invention may be contained in regulators of different forms and to illustrate a practical application of the invention I have 20 selected the pinion and sector type of window regulator to which my invention is applied as an example of the practical applications to which my invention may be put. The construction selected is shown in the accompanying 25 drawing and is described hereinafter.

Figure 1 of the drawing is a perspective view of a part of an automobile, and shows the window regulator mounted in position for raising and lowering the window of the 30 door of the automobile. Fig. 2 is a perspective view of the plate on which the window regulator is mounted. Fig. 3 is an edge view of the window regulator. Fig. 4 is a broken view of the mounting plate shown in Fig. 3. Fig. 5 is a view of a section of the mounting 35 plate, the regulator mechanism being shown removed.

In the particular form of construction shown in the drawings, the regulator is provided with an arm 1 that engages and supports the lower edge of the window 2 of the automobile in the manner well known in the art. The arm 1 is raised and lowered by means of a sector gear 3 which is operated 40 upon by a pinion 4, the pinion 4 being rotated by means of a suitable crank 5. The movable parts of the window regulator are supported on a mounting plate 6.

The mounting plate 6 is an oblong piece 50 of sheet metal which has the ridge or channel

7 located in the central portion thereof and which extends at least the major distance between the pivot points of the pinion 4 and the sector 3. Owing to the location of the channel or ridge 7, the possibility of the bending of the plate by reason of the severest strains that the regulator may be subjected to will be entirely obviated with the result that the meshing relation between the pinion and the sector gear will be maintained and consequently stripping of the gears will be avoided.

I find it preferable, however, to extend the channel or ridge to the pivot points or beyond the pivot points. In the form of construction shown, the channel 7 is enlarged or the plate is recessed so as to receive the pinion at one end and to form a bearing for the sector at the other end. In this form of construction the sector gear 3 is made in the 70 form of a semi-annulus and the ends of the sector gear are secured to the arm 1. The arm 1 is pivotally connected on the top of the ridge or channel, or, in the form of construction shown, to the top of the enlarged portion 75 of the channel located at the end. Thus the arm is located on the side of the plate opposite to that on which the pinion 4 is located. The enlarged cylindrical recess or part of the channel form a large lateral bearing area 80 for the arm. The sector 3 extends through openings 11 which have dimensions substantially the same as the cross sectional area of the sector 3 and which are located in opposite sides of the channel and substantially on opposite sides of the point at which the pinion 85 engages the sector. Thus by my invention is provided a means whereby any twisting action that may be brought to bear upon the roller or pin commonly used at the end of the arm 1 to connect it with the window 2, will be resisted by the large contact area formed by the outer surface of the large cylindrical recess located at the lower end of the channel and any lateral angular movement of the 90 outer edge of the sector relative to the pinion will be prevented by reason of the channel and its location between the pivot points of the sector and the pinion and shifting of the 95 sector gear at its point of engagement with

the pinion either laterally or edgewise will be obviated by reason of the fact that the sector extends through the openings formed in the upper end of the channel on opposite sides of the point of engagement with the pinion while the pinion is located in the cylindrical recess formed in the upper terminal of the channel.

I claim:

1. In a window regulator, a sheet metal mounting plate, a sector and pinion pivoted on the mounting plate, the mounting plate having a channel formed therein and extending from the pivot of the pinion substantially to the pivot of the sector, the pinion located in one end of the channel and the plate having openings formed in the opposite sides of the channel for receiving the sector on opposite sides of the point where it is engaged by the pinion.
2. In a window regulator, a sheet metal mounting plate, the mounting plate having a centrally located channel and cylindrical recesses located in the ends of the channel, a pinion pivotally mounted in one of the recesses, an arm for engaging the window for raising and lowering the window, a sector, the ends of the sector connected to the arm, the channel having openings located in its sides for receiving the sector, the arm located on the side of the plate opposite to that on which the pinion is located, a pin for pivotally supporting the arm and extending through the other of the recesses.
3. In a window regulator a sheet material mounting plate and sector and a pinion, the pinion and the sector pivoted on the mounting plate, an arm for raising and lowering the window, the arm connected to the sector, recesses formed in the plate at the pivot points of the pinion and the sector, the mounting plate having a ridge extending between the recesses, the pinion located in one of the recesses and the sector having a lateral bearing on the outside of the other of the recesses.
4. In a window regulator a sheet material mounting plate, said mounting plate having a centrally located ridge and cylindrical recesses, a pinion pivotally mounted in one of the recesses, the ridge extending from the recess containing the pinion toward the other of the recesses, an arm for engaging the window raising and lowering the window, a sector, the ends of the sector connected to the arm, the ridge having openings in its sides for receiving the sector, the arm located on the side of the plate opposite to that on which the pinion is located, a pin for pivotally supporting the arm and extending through one of the recesses.
5. In a window regulator a sheet metal mounting plate, the mounting plate having a recess, a pinion pivotally mounted in the recess, an arm for engaging the window for

raising and lowering the window, a sector strip, the ends of the sector strip connected to the arm, the recess having openings located in its sides for receiving the sector, the arm located on the side of the plate opposite to that on which the pinion is located and means for pivotally supporting the arm on the mounting plate.

6. In a window regulator, a supporting plate having a boss, a chamber formed within the boss, a pinion located in the chamber, a sector rack engaged by the pinion, the boss having a slot for receiving the sector rack.

7. In a window regulator, a sheet metal supporting plate having a recess formed in the sheet metal supporting plate, a pinion located in the recess, an arcuate strip having a rack formed thereon and engaged by the pinion, the sheet metal supporting plate having a pair of slots located in the side walls of the recess for receiving the strip.

8. In a window regulator, a supporting plate having a portion displaced with reference to the body portion of the plate, a pinion pivotally supported in the displaced portion, a curved strip having teeth on one edge thereof and meshing with the pinion at a point between the displaced portion and the body of the plate, and the supporting plate having a U-shaped ridge extending substantially from pivot of the pinion to the pivot of the arm, the curved strip extending through the ridge.

9. In a window regulator, a sheet metal mounting plate having a raised portion, a rack rotatably supported on one side of the plate and a pinion rotatably supported on the other side of the plate, the rack extending through the plate and meshing with the pinion.

In testimony whereof I have hereunto signed my name to this specification.

HUBERT A. MYERS.
